UNITED STATES PATENT OFFICE.

CHARLES P. SHARRER, OF SYRACUSE, NEW YORK, ASSIGNOR OF ONE-HALF
TO EDWIN H. CROLY, OF SAME PLACE.

RAILWAY-RAIL SPLICE.

SPECIFICATION forming part of Letters Patent No. 349,958, dated September 28, 1886.

Application filed June 28, 1886. Serial No. 206,462. (No model.)

To all whom it may concern:

Be it known that I, CHARLES P. SHARRER, of Syracuse, in the county of Onondaga, in the State of New York, have invented new and 5 useful Improvements in Railway-Rail Splices, of which the following, taken in connection with the accompanying drawings, is a full, clear, and exact description.

This invention has reference to that class of 10 rail-splices in which a fish-plate on one side of the meeting ends of the rails has rigidly affixed to it lugs or tenons formed dovetail at their extremities and projecting through mortises in the stems of said rails, and a fish-plate on the 15 opposite side of the rails is provided with a dovetail longitudinal groove and slipped endwise over the protruding ends of the tenons, and with the latter entered into the aforesaid groove.

20 In order to permit of tightening the hold of the said fish-plate on the rails, it has hitherto been deemed necessary to make the flanges of the lug or tenon wedge-shaped, and to provide the grooved fish-plate with tapering jaws and 25 flanges for the purpose of drawing the two fish-plates toward each other and tightening the same against opposite sides of the rails. This construction, however, is very expensive, as it is difficult to either cast, forge, or swage 30 the plates with their aforesaid tapering or wedging parts, and in driving the grooved plate so as to tighten it on the tongues or tenons of the other plate the former is liable to be either battered up on the driving end or split 35 longitudinally along the groove, which latter weakens the plate along its longitudinal central line.

The object of this invention is to simplify the 40 construction of the fish-plates, and to provide cheap, convenient, and effective means for tightening the hold of said plates on the rails spliced thereby; and to that end my invention consists in the combination, with the rails provided with orifices through their stems, of a 45 straight fish-plate on one side of the rails having affixed to it dovetailed tenons formed longitudinally straight and parallel with said plate, a straight fish-plate on the opposite side of the rails provided with a dovetailed longitudinal groove formed likewise longitudinally 50 straight and parallel with the plate, and a

wedge provided with longitudinal slots and inserted endwise between the grooved plate and stems of the rails, all as hereinafter fully described, and specifically set forth in the claim. 55

In the annexed drawings, Figure 1 is a side view of my invention. Fig. 2 is a side view of the rails without the splicing-plates. Fig. 3 is a detached isometric view of one of the splicing-plates. Fig. 4 is a transverse section 60 of my invention, and Fig. 5 is a detached isometric view of the wedge by means of which the hold of the splicing-plates is tightened.

R R represent the meeting ends of two rails to be spliced together. The end portions of 65 said rails I provide each with one or more orifices or mortises, a a, through the stem thereof.

A and B designate the splicing-plates of the species usually denominated "fish-plates." Both of said plates are perfectly straight longitudinally. The plate A, I provide on the side adjacent to the rails R R with dovetailed tenons t t, distributed over the length of the plate in the same relative positions as the orifices or mortises a a a a of the two rails to be spliced. 70 Said tenons are of such dimensions as to allow them to project through the aforesaid orifices or mortises when the plate A is placed against the side of the end portions of the two rails. The tenons t t are perfectly straight longitudinally 75 and parallel with the plate A. The plate B, I provide on the side adjacent to the rails with a longitudinal dovetailed groove, b, which extends through the end of the plate, and is longitudinally straight and parallel with the plate, 80 and of proper depth and width to allow the plate to be slipped endwise over the tenons t t and closely embrace the top and bottom of the dovetailed portion of said tenons by the top and bottom sides of the groove b, as illustrated 85 in Fig. 4 of the drawings. The engagement of the dovetailed groove b with the dovetailed tenons t t serves to securely tie the two plates together.

w denotes a wedge, which is provided with 90 longitudinal slots s s, of greater length than the tenons t t. This wedge I place with its thin end onto the protruding tenons t t before applying the grooved plate B, and after the latter is slipped onto the tenons I drive the wedge 95 from its large end endwise until it becomes securely set or fastened in its position, thereby 100

effectually tightening the plates A and B against opposite sides of the rails. When the wedge is made of steel, I prefer to curve it longitudinally, as shown in the drawings, so as to cause 5 it to act as a spring and guard against excessive strain on the plates A and B when driving said wedge.

The described fish-plates I provide with additional holds on the rails and with bearings 10 on the cross-ties by forming them with wide flanges c c, which project from the bottom of the fish-plates and lie closely against the top and side edges of the base of the rails, and terminate flush with the under side of said base. 15 The edge of the flange c, I provide with a notch or notches, through which to drive a spike or spikes into the subjacent cross-tie. The head of the spike, bearing on top of the flange c, holds the splice firmly on the tie.

20 I do not claim, broadly, the combination, with the rails having orifices through them, of fish-plates on opposite sides of said rails and provided with interlocking tongues and grooves, as I am aware the same is not new; but

What I do claim as my invention is—

The combination, with the rails provided with the orifices a a a a, of the straight plate A, having affixed to it the dovetailed tenons t t, formed longitudinally straight and parallel with said plate, the straight plate B, provided with the dovetailed groove b, formed likewise longitudinally straight and parallel with the plate, and the wedge w, provided with the longitudinal slots s s, and inserted endwise between the plate B and stems of the adjacent 30 end portions of the rails, substantially as described and shown.

In testimony whereof I have hereunto signed my name and affixed my seal, in the presence of two attesting witnesses, at Syracuse, in the 40 county of Onondaga, in the State of New York, this 26th day of June, 1886.

CHARLES P. SHARRER. [L. S.]
